UNITED STATES PATENT OFFICE.

THOMAS N. WILSON, OF SPOKANE, WASHINGTON, ASSIGNOR OF ONE-HALF TO AARON G. WITMER, OF PORTLAND, OREGON.

TROWEL.

1,166,293.

Specification of Letters Patent. Patented Dec. 28, 1915.

Application filed February 25, 1915. Serial No. 10,478.

To all whom it may concern:

Be it known that I, THOMAS N. WILSON, a citizen of the United States, residing at Spokane, in the county of Spokane and 5 State of Washington, have invented certain new and useful Improvements in Trowels; and I do declare the following to be a full, clear, and exact description of the invention, such as will enable others skilled in the art 10 to which it appertains to make and use the same.

This invention relates to improvements in trowels and more particularly in the means for connecting detachable handles thereto.

15 The object of the invention is to provide a trowel constructed with a removable handle with simple means for firmly clamping the handle to the blade.

Another object is the arrangement in a 20 trowel of a bead or securing strip rigidly connected with the blade of the trowel and designed to be engaged by a reciprocating clamping member being designed to be locked in adjustable position by an eccentric 25 bolt.

With the above and other objects in view, the invention consists of certain novel features of construction, combination and arrangement of parts as will be more fully described and claimed.

30 In the accompanying drawings:—Figure 1 represents a side elevation of a trowel embodying this invention. Fig. 2 is a detail longitudinal section on an enlarged scale. Fig. 3 is a transverse vertical section taken 35 on the line 3—3 of Fig. 1. Fig. 4 is a detail perspective view of the lever used in connection with the handle and the blade. Fig. 5 is a horizontal section taken on the line 40 5—5 of Fig. 2.

In the embodiment illustrated, a trowel blade 1 is shown having a handle 2 removably mounted thereon. The blade 1 has rigidly secured thereto, a bar or bead 3 here 45 shown of dove-tail construction in cross section with its upper face rounded to facilitate the attachment of the handle clamping member 4. This member 4 is here shown in the form of an upright shank 5 having 50 an enlarged head 5' at one end provided on its lower face with a longitudinally extending dove-tail groove 6 which is shaped to fit and slide on the rib 3 of the blade 1 for adjustably connecting the handle clamp-

ing member 4 to said blade by means to be 55 described.

An arm 7 extends laterally from the shank 5 in a plane at right angles thereto and on which the handle 2 is designed to be mounted and held in operative position 60 by any suitable means, a nut 8 being here shown screwed on the outer end of the arm 7 beyond one end of the handle 2. The head 5' of the handle shank has a bore 9 extending transversely therethrough and intersecting the groove 6 thereof, the major portion of said bore being disposed in a plane above the plane of the groove.

A yoke-shaped lever 10 is employed for connecting the handle clamp to the rib 3 70 and is designed to straddle the front end of said clamp with the cross bar of said yoke passing over the upper front end of the arm 7. The free ends of this yoke are preferably enlarged and provided with angular apertures 11 which are designed to receive the angular ends 12 of a connecting or locking bolt 13. This bolt 13 is of a length corresponding to the combined thickness of the head 5' and the two arms of the 75 yoke 10 so that when it is inserted through these arms and through the bore 9 in said head, the terminals thereof will be disposed flush with the outer faces of the arms of the lever 10 and thus any possibility of the 80 bolt being accidentally turned is prevented.

Adjacent the angular ends 12 of the bolt 13 are two rounded portions 14 which are designed to fit in the rounded portion of the bore at opposite sides of the head 5'. The 90 central portion of this bolt has an eccentric 15 formed thereon which is designed to be disposed over the rib 3 in position to engage said rib when the parts are assembled, whereby the forcing of the bolt through the 95 apertures 11 and the bore 9 brings the eccentric portion 15 into binding engagement with the upper face of the rib 3 and forces the head 5' upwardly, causing the walls of the dove-tail groove 6 thereof to bear against 100 the under side of the rib 3 and the cam to grip the upper face thereof and thus securely lock the clamping member 4 to said rib. As shown, this bolt 13 has a longitudinally extending slot 16 in the eccentric 15 105 thereof and projecting into a portion of the rounded portions of the bolt and which is designed to render the eccentric portion of

the bolt resilient to facilitate its gripping action on the rib.

When the parts have been assembled as above described, the handle is firmly locked 5 to the blade and the trowel is ready for use and when so assembled no spaces or interstices are left to permit the lodgment of plaster or other material which would prevent proper operation of the handle.

10 By adjustably mounting the handle on the blade 1, the position thereof may be varied so that should a portion of the rib 3 become worn, a new unworn portion may be secured to the clamping member and thus the life of 15 the trowel prolonged.

I claim as my invention:—

1. A trowel comprising a blade having a rib, a handle member mounted to slide on said rib, said member and rib having interlocking connections, and an eccentric member for engaging said rib and locking said interlocking connections in engaged position, said eccentric having a longitudinally extending slot therein to provide resilient 25 gripping faces.

2. A trowel comprising a blade having a longitudinally extending dove tail rib, a handle member having a dove tail groove for slidably engaging said rib, said handle 30 member having a bore extending transversely therethrough in a plane at right angles to and intersecting said groove, and a rotatable locking element disposed in said bore, said element having an eccentric thereon operable on the turning thereof to engage 35 said rib and force said handle member up against the under side of said rib and said element against its upper face for clamping said handle to said rib.

40 3. A trowel comprising a blade having a rib on its upper face, a handle connecting member comprising an upright having a head provided with a longitudinally extending dove-tail groove on its lower face for in-

terlocking engagement with the rib on said 45 blade, said head having a bore extending transversely therethrough and intersecting said groove, the major portion of the bore being disposed in a plane above the groove, means for connecting the handle to said upright, a lever adapted to straddle said upright and having apertures positioned to register with the bore in the head of said upright, and a locking element extending through the apertures in said lever and 50 through said bore, said element having gripping means for engaging the rib when the parts are in assembled position.

4. A trowel comprising a blade having a longitudinally extending dove-tail rib, a 60 handle clamping member comprising a shank having a laterally extending arm at one end and a head at the other, said head being provided with a dove-tail groove on its lower face for interlocking engagement 65 with the dove-tail rib of said blade, said head having a bore extending transversely therethrough and intersecting said groove, a yoke-shaped lever having angular apertures in the free ends of the arms thereof positioned to register with the bore in said head, with the cross bar of said yoke engaging the upper end of said upright, a locking bolt adapted for insertion through the apertured ends of said yoke-shaped member and a bore 70 in said head, said bolt having angular terminals to fit the angular apertures in said yoke-shaped member and provided at its central portion with a resilient eccentric for bindingly engaging the rib for locking the 75 handle to the blade.

In testimony whereof I have hereunto set my hand in presence of two subscribing witnesses.

THOMAS N. WILSON.
